INVENTOR

UNITED STATES PATENT OFFICE.

JOHN LAMANTIA, OF PORT RICHMOND, NEW YORK.

FUSEE AND CAP.

1,138,671.

Specification of Letters Patent.

Patented May 11, 1915.

Application filed December 14, 1914. Serial No. 877,232.

To all whom it may concern:

Be it known that I, JOHN LAMANTIA, a citizen of the United States, residing at Re-frew Place, Richmond avenue, Port Richmond, in the borough of Richmond and State of New York, have invented certain new and useful Improvements in Fusees and Caps, of which the following is a specification.

10 My invention relates to improvements in fusee and caps in which the fusee-case is choked and crimped so as to make an extension of the paper tube; it is covered with a cap which, similar to the fusee-case, is at 15 one end choked and crimped outward, forming an extension which is firmly tied to make a perfect closure and which is protected by a cover.

The objects of my improvements are as 20 follows: 1. To make the end of the fusee-case thicker to withstand any jar when thrown from a train, and, being the extended folded end is firmly tied, that makes it difficult for the end of fusee to break or to 25 open. 2. To protect the lighting end of the fusee with a cap, which makes a closure difficult to be detached from the tube, carrying on its outer choked surface a complementary lighting material which is difficult 30 to become detached from cap. 3. To protect the complementary lighting material (from moisture and wear) with a cover provided with a tape glued at one end to the cap, and at the other end pasted to the 35 fusee, so that, should the cap be accidentally detached from the tube, it could not ignite the fusee until the aforesaid cover is removed.

In the accompanying drawing: Figure 1 40 is a perspective view looking down upon the protecting cover. Fig. 2 is a vertical longitudinal sectional view of Fig. 1. Fig. 3 is a perspective view of the cap showing the end firmly choked and tied. Fig. 4 is a 45 perspective view of the fusee-case showing the end choked, and leaving aperture for the inflammable composition. Fig. 5 is a perspective view of the protecting cover carrying a tape cemented therein.

50 And referring now to the drawing: A. represents my improved tube or fusee-case,

which may be of any desired structure; but preferably cylindrical, as shown in the drawings, and of any suitable material as paper or fiber, containing an inflammable 55 material —a— of any suitable composition, the end —b— is choked and then crimped outward making an extension —c— which is firmly tied at its base leaving a convenient aperture —d— for a highly inflammable 60 composition —e—.

B. is a cap of a suitable length which is adapted to pass over the end —b— and to properly fit on the tube A having its outer end choked and conveniently extended at 65 —f— and firmly closed and tied in —g— and which is provided with a complementary material —h— adapted to ignite the inflammable composition —e—.

C. is a cover which is adapted to pass over 70 the end —i— of the cap B in order to protect the complementary material from moisture and wear and in order to firmly hold the cap B; it carries a tape —k— cemented therein and showing the extended tongues 75 —l, m—, —m— being of a length to extend considerably below the cap B; thus leaving the part —n— to be pasted on the tube —A— at g' while the other tongue —l— is cemented to the cap B at —g''— as 80 clearly shown in the drawings.

Having thus described my invention, what I claim and desire to secure by Letters Patent is:

1. An improved fusee-case composed of a 85 paper tube having its wall at one end choked and then crimped outward, making thus an extension which is firmly tied at the base, and leaving a convenient aperture in its center to carry a highly inflammable 90 material.

2. An improved cap composed of a paper tube of a suitable length, having its wall at one end choked and then crimped outward making thus an extension which is firmly 95 tied and closed so as to leave no aperture or passage whatsoever, the aforesaid extension carrying a complementary material.

JOHN LAMANTIA.
